UNITED STATES PATENT OFFICE.

CLEMENT BOOTH, OF NARBERTH, AND ALFRED CHARLES PAGE, OF PHILADELPHIA, PENNSYLVANIA.

GRINDING-MACHINE.

1,203,844.

Specification of Letters Patent.

Patented Nov. 7, 1916.

Application filed June 17, 1915. Serial No. 34,602.

To all whom it may concern:

Be it known that we, CLEMENT BOOTH and ALFRED CHARLES PAGE, respectively, a citizen of the United States, residing at Narberth, 5 Montgomery county, Pennsylvania, and a British subject, residing at Philadelphia, Philadelphia county, Pennsylvania, have jointly invented certain Improvements in Grinding-Machines, of which the following 10 is a specification.

Our invention is a machine designed to 15 grind surfaces of revolution. Its characteristic purpose is to provide improved mechanism for multiple grinding, and particularly for simultaneously roughing and finishing surfaces of different articles by different operations while further articles to be successively roughened and finished are placed in the machine.

20 The characteristic features of our improved mechanism are fully disclosed in the following description and the accompanying drawings in illustration thereof.

In the drawings, Figure 1 is a broken 25 front elevation of a machine embodying our improvements; Fig. 2 is a part sectional rear elevation of the same; Fig. 3 is an end elevation of the turret carrying the work spindles; Fig. 4 is a part sectional elevation 30 of the right end of the machine; Fig. 5 is a sectional view of details of the construction shown in Fig. 4 for adjusting the upper grinding wheel; Fig. 6 is a sectional view of details of the construction shown in Fig. 4 35 for adjusting the lower grinding wheel; Fig. 7 is a part sectional elevation of the left end of the machine; Fig. 8 is a part sectional plan view of mechanism for operating the work spindles; Fig. 9 is a plan view of the 40 change speed gears for operating the grinding wheels; Fig. 10 is a part sectional plan view of the controlling mechanism for the grinding table and wheels; Fig. 11 is a part sectional side elevation of the construction 45 shown in Fig. 10.

Generally stated, the mechanism is designed to intermittently revolve a turret 1 in which are journaled the work spindles 2, 2' and 2'' (adapted to be revolved in 50 pairs), in combination with a reciprocating table 3 in which are journaled the arbors 4 and 4' of grinding wheels 5 and 5' adapted to be moved into contact with the work to be ground thereby and to be withdrawn therefrom, the grinding wheels respectively ef-

fecting roughing and finishing operations upon separate articles while a further article is being placed for the successive roughing and finishing operations of the wheels.

The bed 6 of the machine has a driving 60 shaft 7 journaled on the rear thereof and driven by a pulley 8, and the shaft has thereon the spur wheels 9, 10, 11 and 12, which engage with the respective spur wheels 9', 10', 11', and 12' revoluble on the 35 shaft 13 and adapted to be automatically fixed thereto by the respective conventional roller clutches 14, the latter being held out of engagement normally by dogs 15 engaging projections 14' on the roller clutch cages. 70

The dogs 15 are adapted to turn on a stationary shaft 16 and have fixed thereto the respective arms 15'. These arms bear against a revoluble shaft 17 which is provided with lugs 17' for striking and rocking the respective arms to effect the withdrawal of the corresponding dogs from the projections 14', whereby the clutches are permitted to act, the lugs on the shaft 17 being so placed that but one acts at a time 80 and the speed being in correspondence with the ratios of the gear train in action. The shaft 17 is provided with a helical gear 17'' which engages with the helical gear 18'' on a shaft 18 turned by a crank handle 18', by 85 which the speed of revolution of the shaft 13 is determined.

The shaft 13 has a double clutch sleeve 20 splined thereon and reciprocated by an arm 21 provided with a yoke 21' which engages the circular channel 20' of the sleeve, the latter being shiftable alternately into engagement with the clutches 22 and 23 on the respective bevel pinions 22' and 23' which are loose on the shaft 13, whereby the 95 bevel pinions are alternately fixable to and revoluble by the shaft. A journaled shaft 24 has fixed thereon a bevel gear 25, which engages with the pinions 22' and 23' and is revoluble in reverse directions by fixing the 100 pinions alternately to the shaft 13.

A gear wheel 25' is fixed on the shaft 24 and engages a gear wheel 26 fixed on a clutch 26', the parts 26 and 26' being loosely mounted on the journaled shaft 27. A pinion 30' fixed to the wheel 26 engages the rack 31' on the table 3 to reciprocate the latter.

A clutch 27' is splined on the shaft 27 and is adapted to be shifted longitudinally 110

thereon by a rod 28 which is adapted to reciprocate within the shaft and is connected with the clutch by the pin 28', the latter being movable in a slot 27" of the 5 shaft. A hand wheel 29 is fixed on the shaft 27 and serves, through the dependent mechanism, to effect an independent operation of the table 3.

The arm 21 is fixed on a journaled shaft 10 30 which has fixed thereon an arm 31. This arm is connected by a link 32 with a lever 33 having a fulcrum 33'. A rod or link 34, which is pivotally connected at its opposite ends to an oscillating arm 35 and a lever 36, 15 has lugs 34' thereon which lie on either side of the lever 33 so as to permit it a limited independent movement with respect to the lever 33. The lever 36 coacts with a detent 37 which is pressed by a spring 37', the lever being movable past the detent by depressing the latter against the action of the spring and being thrown when past the dead center position by the action of the spring 20 through the detent.

25 A striker 3" on the slide 3' of the table 3 is adapted to engage, on the rearward movement thereof, the lever 33 which is rocked thereby to operate the link 32 and throw the clutch sleeve 20 to the neutral position, 30 the link acting on the sleeve through the intermediate parts 31, 30 and 21.

A bearing 38 on the slide 3' has journaled therein a shaft 39 on which is fixed a lever 40 provided with a striker 40' and a roller 35 40", the striker being adapted for engaging the projections 34" fixed to and adjustable on the link 34 and the roller being adapted for engaging a cam 41' fixed to and adjustable on the way 41. When, by the rearward 40 movement of the slide 3', the striker 40' engages the right projection 34", the link 34 and the lever 36 are shifted thereby to the position shown in Fig. 1. That is to say, the lever is forced past the detent 37 by pressing it down against the spring 37' and is thrown and retained in the position to which it is thrown by the rise of the detent, the movement effecting the further movement of the link 34 and engaging the clutch sleeve 20 45 with the clutch 23 by the action of the link through the parts 33, 32, 31, 30 and 21. The movement of the slide 3' in the opposite direction causes the striker 40' to engage with the left projection 34", whereby the link 34 50 is shifted and acts through the parts 33, 32, 31, 30 and 21 to shift the clutch sleeve 20 into engagement with the clutch 22, the detent 37 acting on the lever 30 when past the dead center position to effect the full throw 55 of the mechanism. In the movement of the slide 3', as the striker 40' travels between the projections 34", the roller 40" engages the inclined surface of the cam 41', which rocks the lever 40, thereby turning the shaft 39. 60 65 This movement of the shaft 39 rocks an arm

42, which lies between collars 43' on a longitudinally movable rod 43, the lever and rod being held in the desired position by the coaction of a notched arm 42' on the lever with a detent 42" pressed by a spring 42". The rod 43 is provided with the slotted clevis 43" which is loosely engaged with a dog 44 through a pin 44' thereon, the clevis having a limited movement independent of the pin. 70

The dog 44 is adapted for engaging a projection 45' fixed to the roller clutch cage 45, and is provided with a lug 44" to be engaged by a lug 46' on the plate 46 to disengage the dog from the projection and with the roller 46" for engaging the lug to throw the dog back into position for reengaging the projection. 75

80 The roller 46" is made adjustable on the plate 46 by providing the latter with the circular T-slot 46", in which is engaged a T-bolt 46' having the roller journaled thereon.

85 A peripheral cam 46' on the plate 46 is adapted for engaging a cam 51' on a lever 51 which is thereby caused to engage the clevis 43" to move the rod 43 longitudinally in the direction of the arrow. Thus the arm 42 and lever 40 are rocked so that the striker 40' is moved out of line with the projections 34", the arm 42' being thrown from the position shown in Fig. 10 in the direction of the arrow and held by the detent 44 in its second position. 90

95 The plate 46 is fixed to a sleeve 46", which is journaled in a bearing 3" of the table 3 and revolved by a pinion 47 fixed thereon. A shaft 48 is journaled in the sleeve 46" and revolved by the clutch cage 45 which is fixed thereto, the shaft having fixed thereon a planetary gear cage 48'. A stub shaft 48" is carried by the cage 48' and has journaled thereon the connected differentials 49 and 49', the latter meshing with the pinion 47 and the former engaging a stationary gear 50 fixed to the bearing 3" concentric with the cylindrical sleeve 46". 100

105 The pulley 52, loose on the shaft 48, is engaged thereto by the roller clutch mechanism comprising the part 45, and is driven by a belt 53 passing over the shaft 7 and movable along the same with the longitudinal reciprocation of the grinding table 3. 110

The sleeve 46" has fixed thereon two cams 54 and 55 on which ride the arms 56' and 57' of the levers 56 and 57. 115

120 A slide 58 is movable on a way 3" of the table by a spring 59 which is connected with the table by a bolt 60 and bears against a lug 58' on the slide, the movement of the slide being regulated by the lever 56 whose arm 56" engages an adjustable stud or screw 58" on the slide, and the movement of the lever being regulated by the engagement of its arm 56' with the periphery of the cam 54. 125

130 A slide 61 is movable on the slide 58 by means of a screw 62 which is journaled in

the slide 58 and feeds through the lug 61' on the slide 61, the screw being turned by a hand wheel 62'. A bearing 61'' on the slide 61 has journaled therein the arbor 4' of the lower grinding wheel 5'. It will be understood that the wheel 5' is moved in a direction transverse to its axis by turning the hand wheel 62', which acts through the parts 62 and 61 to shift the spindle 4', and a further limited movement of this grinding wheel is provided by the play of the slide 61 subject to the control of the parts 54, 56 and 59. The spindle 4' of the upper grinding wheel 5 is similarly journaled in a bearing 63'' of a slide 63 which is movable on a slide 64 by a screw 65 operated by a hand wheel 65', the screw engaging a lug 63' of the slide 63. This mechanism is provided with a lug 64', spring 66 and bolt 67 similar to and for the same purpose as the parts 58', 59 and 60.

The slide 64 has pins 64'' movable longitudinally therein and supported by a revoluble face cam 68 provided with the circular cam groove 68', which engages corresponding ends of the pins so that either may be thrust forward to regulate the relation of the lever 57 to the slide. It will be understood that the contact of the revolving cam 55 with the arm 57' of the lever 57 causes the arm 57'' to act through the contacting pin 64'' upon the slide 64, the cam limiting the action of the spring 66 in moving the slide and positioning the grinding wheel 5 with reference to the work.

The spindles 4 and 4' have pulleys 4^a and 4^b thereon over which and the driving pulley 69 passes a driving belt 70. The belt is tightened by a pulley 71 carried by an arm 72 which is fulcrumed on the slide 60 and actuated to hold the pulley by a spring 73 connected to the arm 72' fixed to the arm 72.

The spindles 2 and 2' hold, by means of chucks 2^a and 2^b thereon, rings 2^a and 2^b to be ground by the roughing wheel 5 and finishing wheel 5' respectively, while the third chuck 2^c on the spindle 2'' is having an undressed ring 2^c placed therein.

When the roughing operation on the ring 2^a and the finishing operation on the ring 2^b have been completed, the table 3 is moved back to withdraw the wheels 5 and 5' and the partial revolution of the turret is effected to move the undressed ring 2^c into line with the wheel 5, the roughly finished ring 2^a into line with the finishing wheel 5', and the finished ring 2^b into position for removal and the substitution of an undressed ring therefor.

The desired intermittent revolution of the turret 1, which is journaled in bearings 74' and 74'' of the housing 74, is effected by a spur wheel 75 fixed to the rear thereof and driven by the spur wheel 76 on a stub shaft 65.

The wheel 76 is driven by a spur wheel

78 which is fixed on a sleeve 79' of a roller clutch mechanism 79, the latter being revoluble on the shaft 80 having the driving pulley 80' fixed thereon. The clutching device 79 is adapted to be automatically engaged to the spur wheel 81 which is fixed on the shaft 80, and is released through the engagement of the lug 79^a by a dog 82' fixed on a shaft 82, the latter having an arm 82'' fixed thereon on which is a roller 82^a. This roller rests upon the periphery of the turret 1 which is provided with three flat or cam surfaces 1' adapted for registration with the roller.

A handle 83' is fixed on a journaled shaft 83 which has fixed thereon a yoke 83''. This yoke engages a collar 84 which has a limited movement on the pin 85, a coiled spring 86 being disposed on the pin between its bearing 85' and the collar 84. The pin 85, which is adapted for engagement in recesses 1'' spaced 120 degrees apart in the periphery of the turret 1, is engaged by an arm 87' fixed on a journaled shaft 87, the latter having an arm 87'' fixed thereon. A link 88 connects the arm 87'' with an arm 82' fixed on the shaft 82.

When the handle 83' is operated, it acts, through the intermediate mechanism described, to withdraw the pin 85 from its engagement with the turret 1, and, by reason of a limited movement of the pin independent of the arm 87', subsequently acts through the intermediate mechanism described, to withdraw the dog 82' from its engagement with the projection 79^a. The turret is thereby permitted to revolve, through the action of the pulley 80 and the intermediate mechanism previously described. When the turret has moved through approximately 120 degrees the roller 82^a registers with the succeeding cam surface 1' and the spring actuated bolt 85 positively shifts the dog 82' to position for engaging the projection 79^a; the clutching mechanism comprising the part 79 being disengaged and the bolt engaging the turret, which is stopped with the spindles in position for a further operation.

The shaft 83 has fixed thereon an arm 83^a, restrained by a spring 89, and is connected by a link 90 with a lever 91, the latter having a roller 91' thereon. A crank lever 92 is provided with the bifurcations 92' adapted to be struck by a roller 3^a on the slide 3' and with the arm 92'' adapted for engaging the roller 91', whereby the bolt 85 is locked in engagement with and holds the turret 1 during the grinding operation. When, at the end of this operation, the table 3 is moved backward, the roller 3^a passes over the first bifurcation 92', strikes the second, and rocks the lever 92, thus disengaging the arm 92'' from engagement with the roller 91' and permitting the operation of the

- mechanism which withdraws the pin or bolt 85. When the table is again moved to the forward position, to position the mechanism for effecting the succeeding grinding operation, the roller 3^a passes over the nearest bifurcation 92', strikes the second and rocks the lever 92, whereby the arm 92'' reengages the roller 91' and the bolt 85 is caused to lock the turret 1 in the second position.
- 10 The spindles 2, 2' and 2'' are revolved by the pulley 80' through the shaft 80, clutch 79, and spur wheel 81 which drives a spur wheel 93 that is loose on the journaled shaft 94 and adapted to be fixed thereto by the roller ratchet 95.
- 15 The shaft 94 acts through the spur wheel 96 fixed thereon to drive a spur wheel 97 fixed on a shaft 98, the latter having fixed thereon a sprocket wheel 99 which acts 20 through a chain 100 to drive a sprocket wheel 101 fixed on the journaled shaft 102.
- 25 A spur wheel 103 is fixed on the shaft 102 and engages the gears 104, 104' and 104'' on the respective work spindles 2, 2', and 2'', the gears on the spindles being automatically fixed thereto by respective roller clutches 105, 105', and 105''. These clutches are respectively provided with lugs 105^a, adapted to be engaged, successively as the 30 turret is intermittently revolved, by a dog 106, so that the spindle to which work is being applied shall remain stationary while the others revolve the work held thereby in engagement with the grinding wheels 5 and 5'.
- 35 The shaft 94 has a double clutch sleeve 109 splined thereon and movable into engagement with the clutch 110' on the spur wheel 110 and the clutch 111' on the spur wheel 111 alternately, the sleeve being shifted by means of a crank 112 having a yoke 112' which engages the sleeve's channel 109'. The wheels 110 and 111 mesh with the respective spur wheels 113 and 114 fixed on 40 the shaft 80.
- 45 When it is desired to increase the speed of revolution of the work spindles 2, 2' and 2'' beyond that obtained by the described action through the wheel 93, the crank 112 is operated to engage the wheel 110 or 111 to the shaft 94, depending upon the particular speed desired, and this shaft is thereby revolved at a speed greater than that otherwise transmitted through the wheel 55 93 so that the latter now revolves idly, since its clutch 95 will not engage.
- 50 It will be understood that the grinding wheels 5 and 5' are reciprocated in the work by a limited reciprocation of the table 3 through the automatic action of the mechanism; for, as has been shown, as the table 60 reciprocates its movement is stopped and reversed by communicating the table's movements through the parts 34, 33, 32, 31, 30 and 21 to the driving clutch sleeve 20, to reverse its connections.
- 65 In both the forward and rearward movements of the table 3, the engagement of the roller 40' with the cam 41 operates the levers 40 and 42, applies tension to the rod 70 43, withdraws the dog 44 from the projection 45', permits the corresponding clutch mechanism 45 to engage the shaft 48 to the pulley 52 and causes the shaft to intermittently operate the sleeve 46'' with the cam 75 plate 46 thereon, through the planetary train 48', 49, 50, 49' and 47, the cam plate being advanced a step by each reciprocation of the table and the dog 44 being automatically actuated by a spring 44^b to reengage the 80 projection 45', disengage the clutch and restore the parts 43, 42, 39, 40, 40' and 40' to normal position. After the necessary limited reciprocations of the table or carriage 3, the intermittently turning cam plate 85 46 causes the engagement of its cam 46^c with the cam 51', rocks the lever 51, shifts the rod 43 in the direction of the arrow thereon, and throws the levers 42 and 40 so that the striker 40' is moved out of line with 90 the projections 34, the mechanism being held in this position by the engagement of the detent 42^a with the arm 42' in the second position to which it has been shifted. The table 3 is thus permitted to continue 95 its rearward movement until the projection 3'' contacts with the arm 33 and throws the clutch 20 to its neutral position. As a part of this operation, the lug 46' on the plate 46 engages the lug 44'' on the dog 44 which 100 is thrown back and throws its notched arm 44^b to its second position with relation to a detent 44^c pressed by a spring 44^d, the parts being held in this position and the clutch 45 continuing to act until the revolution of 105 the plate 46 causes its roller 46^b to engage the roller 44^a, the dog being thereby thrown back to position for reengaging the clutch member 45' and the spring 44^e acting to hold it in this position. As a further part 110 of this operation, the roller 3^a throws the crank lever 92 and disengages the lever 91 so that the pin 85 can be withdrawn from its engagement with the turret 1. The table 3 having reached the limit of its rearward 115 movement, the operator presses down upon the handle 83' and rocks the shaft 83 which acts through the yoke 83'' to withdraw the pin 85 from its engagement with the turret 1, and the pin acts through the parts 87', 120 87, 87'', 88, 82^a and 82 to withdraw the dog 82' from the lug 79^a, whereupon the clutch device 79'' engages and the turret is revolved to bring the spindles 2'' and 2 in line with the respective wheels 5 and 5'. The 125 turret is automatically stopped and locked through the registration of the roller 82^a with a corresponding cam surface 1'; the

plunger 82^c being actuated by the spring 82^d to cause the dog 82^e to engage the lug 79^a, which disengages the clutch 79^b and the pin 85 being elevated by the spring 89 to enter a turret recess 1^c. The lever 33 is then thrown farther manually to cause the clutch sleeve 20 to engage the clutch 23, whereupon the table 3 is caused to move forward to reengage the wheels 5 and 5' with the work by the action of the shaft 13 through the intermediate parts 20, 23, 23', 24, 25', 26, 30, and 31, the pin 85 being locked in engagement with the turret 1 by the action of the roller 3^a on the lever 92 so as to cause the arm 92^c to act on the roller 91^c, which acts through the parts 91, 90, 83^a, 84^a and 86.

Having described our invention, we claim:

1. In a grinding machine, a revoluble turret, a plurality of work holding spindles journaled in said turret, mechanisms for revolving said spindles, and means for disengaging mechanism for revolving the respective spindles, whereby they are thrown out of action, in combination with a reciprocating device, a plurality of spindles journaled in said device, and tools carried by said spindles second named for operating on work carried by said spindles first named.

2. In a grinding machine, a revoluble turret, a plurality of work holding spindles journaled in said turret, mechanisms for revolving said spindles, and means controlled by said turret for disengaging in succession the mechanisms for revolving the respective spindles, in combination with a reciprocating carriage, spindles journaled in said carriage, and grinding wheels carried by said spindles second named for operating on work carried by said spindles first named.

3. In a grinding machine, a revoluble turret, a plurality of work holding spindles journaled in said turret, mechanisms comprising clutches for revolving said spindles and means for disengaging the respective clutches in succession by the intermittent revolution of said turret, in combination with a reciprocating carriage, spindles journaled in said carriage, grinding wheels carried by said spindles second named for acting upon work revolved by said spindles first named, and means for automatically reciprocating said carriage.

4. In a grinding machine, a revoluble turret, mechanism for revolving said turret, mechanism for automatically stopping said turret in predetermined positions, a plurality of work holding spindles journaled in said turret, mechanisms for revolving said spindles, and means for disengaging the mechanisms for revolving the respective spindles in predetermined positions thereof, in combination with a reciprocating car-

riage, spindles journaled in said carriage, 65 and grinding wheels carried by said spindles second named for operating on work carried by said spindles first named.

5. In a grinding machine, a revoluble turret, mechanism for revolving said turret, 70 mechanism for locking said turret in predetermined positions, a plurality of work holding spindles journaled in said turret, mechanisms for revolving said spindles, and means for disengaging the mechanisms for 75 revolving the respective spindles in succession in predetermined positions thereof, in combination with a reciprocating carriage, spindles journaled in said carriage, means whereby said spindles last named are adapted 80 to be reciprocated transversely to the direction of reciprocation of said carriage, and grinding wheels carried by said spindles last named for operating on work revolved by said spindles first named. 85

6. In a grinding machine, a revoluble turret, mechanism for revolving said turret, mechanism for automatically stopping and locking said turret in predetermined positions, a plurality of work holding spindles 90 journaled in said turret, mechanisms comprising clutches for revolving said spindles, and means for automatically disengaging the clutches of the respective spindles in predetermined positions thereof, in combination with a reciprocating carriage, spindles journaled in said carriage, grinding wheels carried by said spindles last named for acting on work carried by spindles first named, and means for automatically reciprocating said carriage with said wheels in contact with said work. 95

7. In a grinding machine, a revoluble turret, mechanism for automatically engaging and holding said turret in predetermined 105 positions, mechanism comprising a clutch for revolving said turret, mechanism whereby the operation of said mechanism first named to release said turret disengages said clutch to permit said mechanism second 110 named to revolve said turret, and mechanism operating under control of said turret whereby in predetermined positions thereof said clutch is automatically disengaged.

8. In a grinding machine, a revoluble turret, driving mechanism for revolving said turret, means for disengaging said driving mechanism, locking mechanism for holding said turret in predetermined positions, 115 means for disengaging said locking mechanism, means whereby the disengagement of said locking mechanism effects the engagement of said driving mechanism, a plurality of spindles journaled in said turret, mechanisms for revolving said spindles, and means 120 for disengaging said mechanisms last named in predetermined positions of said turret. 125

9. In a grinding machine, a revoluble tur-

- ret, driving mechanism for revolving said turret, means for automatically disengaging said driving mechanism and locking said turret in predetermined positions thereof, a plurality of work holding spindles journaled in said turret, means coöordinated with said driving mechanism for revolving said spindles, and mechanism for automatically disengaging the driving means for the respective spindles in succession in predetermined positions thereof.
10. In a grinding machine, a revoluble turret, driving mechanism comprising a clutch for revolving said turret, means for disengaging said clutch and holding said turret, work spindles journaled in said turret, mechanisms comprising clutches coöordinated with said driving mechanism for revolving said spindles, and means for disengaging said clutches last named in predetermined positions of said spindles.
11. In a grinding machine, a revoluble turret having a gear thereon and driving mechanism comprising a revoluble shaft, a gear loosely mounted thereon, means for clutching said gear to said shaft, and a gear connecting the gears aforesaid, in combination with work spindles journaled in said turret, gears on the respective work spindles, clutches for fixing the gears last named to the respective work spindles, a gear for revolving said gears last named, and driving mechanism connecting said gear last named with said shaft.
12. In a grinding machine, a revoluble turret having a gear thereon and driving mechanism comprising a revoluble shaft, a gear loosely mounted thereon, clutching means for engaging said gear to said shaft, a gear connecting the gears aforesaid, and means for automatically disengaging said clutching means, in combination with work spindles journaled in said turret, gears connected with the respective work spindles, clutches for fixing the gears last named to the respective spindles, means for automatically disengaging said clutches in succession in a predetermined position of said spindles, a gear for revolving said gears last named, and driving mechanism connecting said gear last named with said shaft.
13. In a grinding machine, a revoluble turret, mechanism comprising a clutch for driving said turret, and means whereby said clutch is automatically disengaged and said turret is stopped in predetermined positions, said means comprising an oscillating dog for disengaging said clutch, an oscillating arm fixed to said dog, a cam on said turret with which said arm is adapted to engage, a reciprocating bolt for engaging said turret, and means connecting said bolt with said dog and arm.
14. In a grinding machine, a revoluble turret provided with a cam, mechanism comprising an automatically acting clutch for revolving said turret and means whereby said clutch is automatically disengaged and said turret is held in predetermined positions, said means comprising an oscillating dog for acting on said clutch, an oscillating device fixed to said dog and adapted to register with said cam, and locking device for holding said turret, and means connecting said locking device with said oscillating device and dog whereby their actions are co-ordinated.
15. In a grinding machine, a revoluble turret provided with cams, mechanism comprising an automatically acting clutch for revolving said turret, and means whereby said clutch is automatically disengaged and said turret is held in predetermined positions, said means comprising a device for acting on said clutch, a device for engaging said cams to permit said device first named to operate, a device for engaging said turret, mechanism connecting said devices to effect their coöordination, a rock shaft, and means comprising an arm connecting said shaft and device last named for disengaging said turret.
16. In a grinding machine, a revoluble turret and work holders carried thereby, in combination with a reciprocating carriage, a slide movable on said carriage, a spindle journaled in said slide, a grinding wheel on said spindle, and means for reciprocating said carriage, said means comprising a revoluble clutching device and mechanism operated by the movement of said carriage for shifting said clutching device and reversing said movement.
17. In a grinding machine, a reciprocating carriage, a reciprocating slide movable on said carriage transversely to the movement thereof, a spindle journaled in said slide, a grinding wheel on said spindle, means for regulating the movement of said slide, means comprising automatically operated reversing devices for effecting a limited reciprocation of said carriage, and means for periodically shifting reversing devices aforesaid and effecting a fuller movement of said carriage.
18. In a grinding machine, a reciprocating carriage, a spindle journaled in said carriage, and means for reciprocating said carriage, said means comprising automatically operating reversing devices for effecting a limited reciprocation of said carriage and means for periodically shifting reversing devices aforesaid to permit a continuation of the rearward movement of said carriage.
19. In a grinding machine, a reciprocating carriage, devices for automatically reversing the movement of said carriage, and means comprising a revoluble cam for auto-

matically throwing the reversing devices out of action.

20. In a grinding machine, a carriage, means for moving said carriage, devices for reversing the movement of said carriage, and mechanism comprising a revoluble cam, a rock lever operated by said cam, a striker and means whereby said lever shifts said striker to throw said reversing devices out 10 of action.

21. In a grinding machine, a reciprocating carriage, mechanism for moving said carriage, devices for reversing said mechanism to effect the reverse movements of said 15 carriage, means comprising a revoluble member controlled by the movement of said carriage for periodically changing the relation of devices aforesaid to prevent reversing, whereby said mechanism continues to move 20 said carriage rearwardly, means whereby said carriage is stopped in a predetermined position by disengaging said mechanism, means whereby said revoluble member is stopped synchronously with said carriage, 25 means for engaging said mechanism to start said carriage forward, and means whereby said member is started by the movement of said carriage.

22. In a grinding machine, a reciprocating carriage, driving mechanism for moving said carriage, reciprocating mechanism carried by said carriage whereby said driving mechanism is operated to reverse the movement of said carriage, means for 30 throwing said reciprocating mechanism out of coöperative relation to said driving mechanism to prevent reversing, whereby said carriage is permitted to continue its rearward movement, and means on said carriage 35 for disengaging said driving mechanism 40 whereby said carriage is stopped.

23. In a grinding machine, a base, a carriage adapted to reciprocate thereon, driving mechanism for reciprocating said carriage, controlling mechanism carried by said carriage whereby said driving mechanism is caused to reverse the movement of said carriage, means carried by said carriage whereby said controlling mechanism is thrown out 45 of coöperative relation to said driving mechanism at a predetermined stage in the operation, and means whereby said controlling mechanism is automatically thrown by the movement of said carriage into coöperative 50 relation to said driving mechanism.

24. In a grinding machine, a base, a carriage adapted to reciprocate on said base, driving mechanism for reciprocating said carriage, controlling mechanism carried by 60 said carriage whereby said driving mechanism is caused to reverse the movement of said carriage, means comprising a revoluble member carried by said carriage whereby said controlling mechanism is thrown out

of coöperating relation to said driving mechanism, and a cam in the path of movement of said controlling mechanism for throwing it into coöperative relation to said driving mechanism.

25. In a grinding machine, a base, a carriage adapted to reciprocate on said base, driving mechanism for reciprocating said carriage, and means carried by said carriage for controlling said driving mechanism, said means comprising a rocking device, a revoluble member, means whereby said member operates said device to change its relation to said driving mechanism, means comprising a clutch for revolving said member, and means for automatically operating said clutch to control the movement of said revoluble member.

26. In a grinding machine, a base, a carriage adapted to reciprocate thereon, driving mechanism for reciprocating said carriage, and means carried by said carriage for controlling said driving mechanism, said means comprising rocking mechanism adapted to shift said driving mechanism, a link connected with said rocking mechanism to 85 shift the same, a dog adapted to coact with said link, a revoluble member adapted to throw said dog and link, and means comprising a clutch for driving said member, said dog being adapted for operating said clutch. 90

27. In a grinding machine, a reciprocating carriage, driving mechanism for reciprocating said carriage, and means for controlling said mechanism, said means comprising a journaled shaft, means comprising a 100 clutch for driving said shaft, a revoluble member, means comprising a differential power transmitting mechanism whereby said shaft operates said member, a dog operated by said member whereby said clutch is engaged and disengaged, rocking mechanism, and means operating under control of said revoluble member whereby said rocking mechanism is shifted.

28. In a grinding machine, a reciprocating carriage, driving mechanism comprising reversing devices for reciprocating said carriage, and means for controlling said reversing devices, said means comprising a rocking mechanism, a link whereby said rocking mechanism is adapted to be shifted, a lever adapted for shifting said link, a revoluble member adapted for rocking said lever, means comprising a clutch and a differential transmitting mechanism for driving said 110 member, a dog for shifting said clutch to disengage said revoluble member, and means for automatically operating said dog. 115

29. In a grinding machine, a reciprocating carriage, driving mechanism for reciprocating said carriage, rocking mechanism carried by said carriage for controlling said driving mechanism, and means for shifting 120

1. said rocking mechanism with relation to said driving mechanism, said means comprising a link connected with said rocking mechanism, a dog adapted to be operated by 5 said link, a clutch adapted to be disengaged by said dog, a revolute member driven through said clutch, a dog connected with said link, said revolute member having means for operating said dog and said dog 10 shifting said clutch, a lever for operating said link, and a cam carried by said revolute member to operate said lever.
2. In a grinding machine, a reciprocating carriage, mechanism for reciprocating 15 said carriage, means for reversing said mechanism, and devices for controlling said means to periodically avoid reversing, said devices comprising a revolute device, a lever adapted to be rocked by said device, a 20 link operated by said lever, and a device movable by said link out of its operative position.
3. In a grinding machine, a reciprocating carriage, mechanism for moving said 25 carriage, devices for reversing said mechanism to effect the reverse movement of said carriage, means for shifting said devices to prevent reversing whereby said mechanism continues to move said carriage, and means 30 whereby said carriage disengages said mechanism and is automatically stopped.
4. In a grinding machine, a slide, a spindle journaled in said slide, a grinding wheel carried by said spindle and means for 35 controlling the movements of said slide, said means comprising a revolute cam, and means connecting said cam and slide for regulating the position of the latter.
5. In a grinding machine, a revolute 40 work holder, in combination with a slide movable transversely to the axis of said work holder, a spindle journaled in said slide so as to be movable thereby transversely to said axis, a wheel carried by said spindle for grinding said work, and means 45 for controlling the position of said slide to regulate the relation of said wheel to said work, said means comprising a revolute cam for moving said slide.
6. In a grinding machine, a revolute 50 work holder, in combination with a carriage adapted to reciprocate in the direction of the axis of the work holder, a slide on said carriage adapted to reciprocate transversely to said axis, a spindle journaled in 55 said slide, a wheel carried by said spindle for operating on work carried by said holder, and means for regulating the position of said slide, said means comprising a spring, a revolute cam and a lever rocked 60 by said cam.
7. In a grinding machine, a work holder, a carriage adapted to reciprocate to and from said holder, a slide adapted to reciprocate on said carriage transversely to the direction of movement thereof, a spindle journaled in said slide transversely to the movement thereof, a wheel carried by said spindle for grinding work carried by said holder, means comprising controlling 65 devices for reciprocating said carriage, and means for regulating the movement of said slide in coördination to the action of said controlling devices.
- In testimony whereof we have hereunto 70 set our names this 14th day of June, 1915.
- CLEMENT BOOTH.
ALFRED CHARLES PAGE.
